UNITED STATES PATENT OFFICE.

FRANK ENOS, JR., OF NORWICH, CONNECTICUT, ASSIGNOR TO THE NORWICH AUTOMATIC FEEDER COMPANY, OF NORWICH, CONNECTICUT, A CORPORATION OF CONNECTICUT.

ANTIFREEZING DRINKING-FOUNTAIN FOR POULTRY.

1,148,302.

Specification of Letters Patent. Patented July 27, 1915.

Application filed August 12, 1914. Serial No. 856,465.

To all whom it may concern:

Be it known that I, FRANK ENOS, Jr., a citizen of the United States, residing at Norwich, county of New London, State of Connecticut, have invented certain new and useful Improvements in Antifreezing Drinking-Fountains for Poultry; and I do declare the following to be a full, clear, and exact description of the invention, such as will enable others skilled in the art to which it appertains to make and use the same.

This invention relates to certain new and useful improvements in automatic antifreezing drinking fountains for poultry, and the primary object thereof is to provide improved heating means for the reservoir whereby to prevent the water from freezing.

A further object of the invention is to provide means whereby the reservoir may be easily and quickly removed from and applied to the heating means; to enable easy and quick access to the burner and automatic closure of the means of access; to provide a heater structure in which heat is supplied to the entire exterior of the fountain so as to effectively heat same throughout the entire area thereof; and to also provide a drinking cup or trough which can be easily and quickly applied to and removed from the reservoir to allow of cleansing thereof, and to also enable compact assemblage of the parts in packing for shipping purposes.

The invention has further and other objects which will later appear and manifest themselves in the course of the following description.

In the drawings: Figure 1 is a side elevation of the invention; Fig. 2 is a central vertical sectional view; Fig. 3 is a top plan view of the heater means in detached relation to the reservoir; Fig. 4 is an enlarged fragmentary sectional view showing the locking or fastening means for the reservoir and drinking cup in side elevation; Fig. 5 is a similar view of the base of the reservoir showing the fastening means for the removable drinking cup; and Fig. 6 is an enlarged fragmentary view, partly broken away and in section of the bottom portion of the reservoir front.

The invention includes a tank or reservoir 1, having a top water inlet normally sealed by a removable closure 2, whereby water may be placed into the tank. As shown in

my Patent No. 1055624, dated March 11, 55 1913, an air duct 3 is connected to the tank and has its lower end extending into the drinking cup or trough 4, a pipe 5 establishing communication between the duct 3 and the top of the tank. A siphon pipe 6 has one leg disposed within tank 1, and its opposite leg within drinking cup 4, the end of the siphon within the trough being closable by a valve 7 connected to a bar which carries springs 8, whereby the valve is frictionally held in closed position and can be moved down to open position, which means allows water to be fed from the tank to cup 4.

The heater structure consists of a casing 70 having a circular vertical wall 9 and a bottom 10, the wall being provided with a series of upper and lower spaced rows of openings 11, while the inner face of the wall is lined with a screen element 12 which 75 covers the openings 11. The wall 9 is provided with a hand opening 13 around which a door frame 14, is secured, a door 15, provided with a glass covered sight opening 16 or peep-hole, being pivoted at 17 to the 80 frame 14, whereby the action of the burner 18 which is located to the rear of the door may be observed at all times, and be reached by mere opening of the door, the door when released gravitating to closed position. 85

The burner 18, is connected to the oil reservoir 19 which latter seats on the bottom 10. The inner side face of the wall 12 of the heater casing has a pair of vertical guides 20 secured thereto and on opposite 90 sides of the door opening 13, which guides slidably engage with out-turned flanges 21, formed on the free ends of a horizontally disposed U-shaped guard 23, the guard 23 being provided with a rear air inlet 25 and 95 with a top heat deflector 24 which directly overlies the burner so as to protect the bottom of the water tank against the direct action of the heat or flame issuing from the burner 18 and to also deflect the heat to 100 the rear of the burner. A chain 25 is preferably connected to the guard 23 and to the heater casing so as to prevent accidental loss or displacement of the guard 23.

To provide for automatic attachment and 105 ready and easy detachment of the water tank and the heater structure, the latter is provided with an outwardly extending

flange or rib 26 adapted to be engaged on its under face by latches 27, which latter are pivoted to the tank 1, by ears 28, the latches being gravity operated so as to automatically ride over and engage under the rib 26, when the water tank is placed on top of the heater casing.

10 The duct 3 is reduced at 29 to provide a space into which the rear wall of the drinking cup 4 is received. The drinking cup 4 is of arcuate form and has its bottom seated on a rib 30 formed on the bottom of tank 1, and can be easily removed from the tank and applied thereto by a spring 31
 15 which latter is secured by soldering 32 to the contracted part of duct 3 and has its lower end curved at 33 so as to bear against the rear wall of cup 4, the spring further having a struck out finger 34 which extends
 20 in the opposite direction from the lower end of the spring to also bear against the rear wall of the cup 4.

To apply the cup, the rear wall thereof is inserted under the curved end 33 of spring
 25 31 and then moved upwardly to move the finger 34 outwardly to thus enable the latter to also bear against the rear wall of the cup, whereupon the cup is then moved downwardly to have its bottom seat on the rib 30.

30 The cold air enters the lower row of openings 11 and then passes through the opening 35 of the guard 23 to enable air to be supplied to the burner, the hot air passing up over the top of the guard 23 and then passes through the upper row of openings 11 and rises in a thin film-like manner in close proximity to the outer side walls of the water tank so that the latter is thus protected by a surrounding film of hot air thus
 35 preventing freezing of the water in addition to the heat which directly acts on the bottom of the tank. The heater being also disposed adjacent to and beneath the drinking cup also heats the latter as well.

40 45 What is claimed is:—

1. In combination with a water tank, a heater device including a casing having upper and lower circular rows of spaced apertures, a screen covering the openings, an oil reservoir in the casing having a burner, a horizontally disposed U-shaped guard which incloses the burner and has its ends removably secured to the casing, and a horizontal deflector overlying the
 50 55 burner and connected to the guard sides in spaced relation to the closed end of the guard.

2. In a poultry drinking fountain, a heater device, a water tank above said device, said heater device having a door-opening, vertical guides located on opposite sides of the door-opening, a U-shaped deflector having the free ends of its sides turned outwardly and engaged with said guides, and a transverse top plate connected to the deflector sides and spaced from the closed end of the deflector, the closed end of the deflector having a cold air inlet adjacent the bottom thereof, and the top of the deflector being spaced from the bottom of the water tank.

3. In a poultry drinking fountain, a heater device having a door opening, a water tank thereon, a deflector having a closed end and an open end, means to removably connect the open end of the deflector to the heater device in opposite relation to the door opening, said closed end of the deflector having a cold air inlet, and a top plate on the deflector spaced from the closed end whereby heated air will pass up through the space between the plate and the closed end of the deflector and over the closed end, the top of the closed end of the deflector being spaced from the water tank bottom to form a hot air passage.

4. In a poultry drinking fountain, a heater device, a removable oil reservoir therein having a casing provided with lower cold air inlets and upper hot air outlets, a water tank on said device, a deflector having an open top and bottom and a cold air inlet at its base, and also having its top spaced from the bottom of the water tank to provide a hot air passage, and means to deflect heat toward said passage, said deflector being removable and having its base edge seated on the reservoir.

5. In a poultry drinking fountain, a heater device, an oil reservoir having a burner thereon within said device, a water tank on said device, and a deflector composed of a member open at its bottom and seated on said reservoir in surrounding relation to the burner and having its top spaced from the water tank bottom and provided with an opening, said deflector having a cold air inlet at its base.

In testimony whereof I affix my signature in presence of two witnesses.

FRANK ENOS, Jr.
